UNITED STATES PATENT OFFICE.

JESSE WALRATH, OF RACINE, WISCONSIN.

IGNITER-CONTROLLING MECHANISM FOR EXPLOSIVE-ENGINES.

SPECIFICATION forming part of Letters Patent No. 691,509, dated January 21, 1902.

Application filed October 12, 1900. Serial No. 32,880. (No model.)

To all whom it may concern:

Be it known that I, JESSE WALRATH, a citizen of the United States, residing at Racine, in the county of Racine and State of Wisconsin, have invented certain new and useful Improvements in Igniter-Controlling Mechanism for Explosive-Engines; and I do hereby declare the following to be a full, clear, and exact description of the invention, such as will enable others skilled in the art to which it appertains to make and use the same.

My invention is an improvement in mechanism for timing the igniting devices of explosive-engines; and it consists in the novel features hereinafter described, reference being had to the accompanying drawings, which illustrate one form in which I have contemplated embodying my invention, and said invention is fully disclosed in the following description and claims.

In the drawings, Figure 1 represents a portion of an explosive-engine, including the cam-shaft and devices for operating and timing the igniting mechanism, parts being shown in elevation and parts in section. Fig. 2 is a bottom plan view of the igniter-operating cam shown in Fig. 1. Fig. 3 is a sectional view of a sleeve forming part of said cam.

My invention relates to explosive-engines, and consists in mechanism for varying the time at which the ignition of the charge takes place with reference to the movements of the other parts of the engine, and I have shown in the accompanying drawings so much of a gas-engine as is necessary for a comprehension of my invention.

In the drawings, A represents a portion of the engine base or casing.

B represents a shaft for operating the cam which actuates the igniting device and which derives its motion in any desired way from the crank-shaft of the engine. The shaft B will hereinafter be referred to as the "cam-shaft."

C represents a rod or stem which extends to and actuates the igniting mechanism, which will preferably be an electric sparking device. The rod C is given a longitudinal reciprocating movement by means of a cam on the cam-shaft, and in this instance the lower end of the rod C is pivotally connected at c to an arm or link D, which is pivotally con-

nected at its other end on a rod or shaft d. The portion d' of said arm D, which forms the bearing to engage the rod d, is provided with a boss d², having a threaded aperture therethrough disposed transversely to the rod d.

E represents an adjusting-screw which extends through the said threaded aperture in the boss d² and is provided on its inner end with an annular groove or recess e and on its outer end with a head e', adapted to be turned by hand, and in this instance provided with radial projections e² for that purpose. The screw E is also provided with a jam-nut e³, which is also formed with radial projections e⁴ to enable it to be readily turned by hand.

On the lower face of the arm D is a movable controlling-bar F, provided with longitudinal slots f, through which pass screws f', which secure said bar to the arm D, but permit it to move longitudinally. The bar F is provided at its outer end with a downwardly-extending projection f², adapted to engage the igniter-cam, and at its inner end with a downwardly-extending slotted projection or yoke, which engages the annular groove in the end of the screw E. It will thus be seen that by loosening the jam-nut e³ and turning the head e' and screw E the igniter-controlling bar F can be moved longitudinally so as to bring its projection f² into different positions with respect to the cycle of the igniter-operating cam, thus changing the time at which the igniting mechanism is operated with respect to the movement of the crank-shaft and cam-shaft. The casing A is provided with an aperture a, closed by a removable plate a', for the purpose of giving access to the head e' and jam-nut e³ to enable the igniter-controlling bar F to be adjusted from the outside of the engine.

G represents the igniter-operating cam, provided with a grade g, adapted to engage the projection f² of the igniter-controlling bar. In starting an explosive-engine it is sometimes desirable to move the balance-wheel backward instead of forward to place the engine in the most advantageous position for starting it, and I therefore connect the cam G to the cam-shaft B in such a manner that the backward movement of the cam-shaft will not produce any injury to the cam or to the igniter-controlling bar. To this end I

- employ a sleeve H, which is secured rigidly to the cam-shaft by means of a set-screw h and is provided with a ratchet-tooth h'. I prefer to provide the sleeve H with a reduced portion h² to receive the cam G and to form an annular groove h³ in said reduced portion, in the bottom of which is formed the ratchet h'. The cam G is provided with a circular opening to enable it to be slipped upon the reduced portion h² of the collar, and said cam is also provided with a recess g', extending entirely through the cam. In this recess is a pawl g², pivoted at g³ and provided with a spring g⁴, which is secured to the cam and engages the pawl g², so as to force it inwardly. When the cam G is placed upon the sleeve H, the pawl g² will enter the annular groove h³ in said sleeve and be in position to engage the ratchet h' in the bottom of said groove.
- 20 The pawl g² will therefore connect the cam with the sleeve for joint movement when the cam-shaft is revolving in the direction indicated by the arrow in Fig. 1 and will also serve to prevent the cam from moving longitudinally of the cam-shaft by reason of its engagement with the annular groove h³.
- Should the engine be reversed, so as to turn the cam-shaft in the reverse direction, the sleeve H would simply turn within the cam 30 G. When the engine was again operated in the usual manner, the ratchet h' of the sleeve would engage the pawl g² of the cam and the cam would take up its movement with the sleeve and cam-shaft. This construction obviates the danger of injury to the cam and to the projection f² of the igniter-controlling bar, which might result when the engine was turned backward if the cam were rigidly secured to the cam-shaft.
- 40 What I claim, and desire to secure by Letters Patent, is—

1. In an explosive-engine, the combination with the igniter-operating rod, of a pivoted arm having its movable end connected to said rod, an igniter-operating cam, an adjustable

controlling-bar having a sliding engagement with said arm, and provided with a projection for engaging said cam, and devices for securing said bar rigidly to said arm, substantially as described.

2. In an explosive-engine, the combination with the igniter-operating rod, of an arm pivoted to the engine-frame, and having its movable end connected to said rod, an igniter-operating cam, a longitudinally-adjustable controlling-bar having a sliding engagement with said arm, provided with longitudinal slots, and having a projection for engaging said cam, an adjusting-screw on said arm, engaging said controlling-arm, and screws extending through said slots and engaging the said pivoted arm, substantially as described.

3. In an explosive-engine, the combination with the igniter mechanism, of a pivoted arm provided with a threaded sleeve, and having its movable end operatively connected with said igniter mechanism, an igniter-operating cam, an adjustable controlling-bar having a longitudinal sliding engagement with said arm and provided with a projection to engage said arm, and with a yoke, an adjusting-screw engaging said threaded sleeve and having an annularly-grooved portion engaging said yoke, and a set-nut upon said screw, substantially as described.

4. In an explosive-engine, the combination with an igniter-operating rod, a pivoted arm having its movable end connected to said rod, a movable controlling-bar connected to said arm and provided with a cam-engaging part, an adjusting-screw for said bar, a cam-shaft, an igniter-cam on said shaft and a pawl-and-ratchet mechanism connecting said cam and shaft, substantially as described.

In testimony whereof I affix my signature in the presence of two witnesses.

JESSE WALRATH.
